UNITED STATES PATENT OFFICE.

WILLIAM F. SCHACHT, OF HUNTINGTON, INDIANA.

DESIGN FOR A QUOIT GAME APPARATUS.

Application filed February 3, 1926. Serial No. 16,381. Term of patent 14 years.

To all whom it may concern:

Be it known that I, WILLIAM F. SCHACHT, a citizen of the United States, residing at Huntington, in the county of Huntington and State of Indiana, have invented a new, original, and ornamental Design for a Quoit Game Apparatus, as shown in the accompanying drawing, forming part of this specification.

The drawing shows a perspective view showing the design for a quoit game apparatus.

I claim:—

The ornamental design for a quoit game apparatus substantially as shown.

WILLIAM F. SCHACHT.
